UNITED STATES PATENT OFFICE.

EDWIN P. OSGOOD, OF MALDEN, MASSACHUSETTS.

RAILWAY PASSENGER-CAR.

SPECIFICATION forming part of Letters Patent No. 291,764, dated January 8, 1884.

Application filed November 12, 1883. (No model.)

To all whom it may concern:

Be it known that I, EDWIN P. OSGOOD, of 5
Malden, in the county of Middlesex and State
of Massachusetts, have invented a new and use-
ful Improvement in Railway Passenger-Cars;
and I do hereby declare that the following is a
full, clear, and exact description of the same.

My invention relates to railway passenger-
cars; and it consists of a partition of flexible
10 material or fabric adapted to be extended or
contracted, after the manner of a curtain, and
when unrolled or extended to be fixed upon
the back or backs of the seat or seats, for the
purpose of separating the seats, in order to give
15 seclusion to the occupants.

I have hereinafter described the manner in
which I have embodied my invention, and
illustrated the same in the accompanying
drawings, in which—

20 Figure 1 is a view of the back of the seat,
with the partition extending laterally, in side
elevation. Fig. 2 is a perspective view of a
portion of the car, showing the partition at-
tached at one end to the side of the car. Figs.
25 3 and 4 represent modifications.

In Fig. 1 a curtain, A, is represented as at-
tached to a roller, B, which may be an ordinary
spring-roller, like that used upon curtains,
30 connected to the wall by brackets b. The free
end of the curtain is extended by means of a
rod, C, which has bolts c, like a door or shutter
bolt, sliding within it at one end. In the form
35 shown, in which the curtain is extended hori-
zontally, this bolt is in the lower end of the
rod. The roller B is attached to the side of the
car in line with the upper edge of the back of
the seat when said back is in its normal con-
40 dition. The curtain is long enough, when ex-
tended, to reach near the end of the back against
the passage, and a hole or socket is provided
in the back for the bolt c; or in place of the
45 hole a bolt-socket may be attached to the back,
as the workman may prefer. The construction
will be such that when the curtain is extended
and the bolt dropped into its place the curtain
will be held taut, or nearly so. Of course the
50 rod C may be made long enough to be inserted
in the hole without an extensible bolt.

It will be apparent that the roller may be
55 attached to the top of the car and be drawn

down or attached to the top of the back, and
be drawn up with the same general effect, and
I do not limit myself to the particular construc-
tion of the roller or the curtain adapted to be
wound thereon, as a folding flexible curtain 55
may be used, like Venetian blinds, or with folds
like those of a fan. These are details of con-
struction which may be used at pleasure with-
out departing from the spirit of my invention.
By means of this construction, one being placed 60
in line with every seat-back, the occupant of
the seat desiring to be secluded from observa-
tion may draw the curtains, and fixing the rod
C in the socket or hole, may shut off the seat
in front and rear from the rest of the car, ex- 65
cluding observation or shutting out the rays of
the sun or drafts of air from the windows in
front or rear. It may be made strong enough
to serve also as a support for the head. So far
as described, this construction shuts out obser- 70
vation from front and rear; but as it may be
desired to render the seat entirely private, I
may provide the corner rod or post with a cur-
tain similar to the one described, but secured to
said post upon the opposite side therefrom. 75
This curtain is adapted to be secured across
the entrance to the seat, and may be provided
with suitable hooks or catches for connection
with the post upon the seat in front. When
not in use, both curtains would roll evenly up- 80
on the post. This would effectually close up
the entrance to the seat and entirely exclude
observation. Upon these curtains the names
of the stations along the line could be printed,
or they could be ornamented by landscape-pic- 85
tures, or in any suitable or desirable manner.

It will be understood that the manner of
connecting the roller to the wall or ceiling, as
herein explained, may be varied, and any suit-
able well-known mechanical means may be 90
employed for the purpose.

Instead of securing the curtain to the wall
directly in line with the back of the seat, it may
be secured at any convenient point and be di-
rected under a guide secured to the wall in line 95
with the back of the seat, as shown in Fig. 2.

It may also be found preferable in some cases
to have the curtain simply attached to two rods
or posts adapted to be inserted in sockets at
each end of the back of the seat, the whole be- 100

ing capable of being rolled up and placed within a case, as in Fig. 4, which may be attached to the wall of the car, or may be placed in any convenient position. In this case the spring-
5 roller would not be necessary.

I am aware that flexible and extensible partitions for sleeping-cars to divide the berths thereof are not new, and, further, that it has been proposed to provide a partition adapted
10 to be folded between the seats of an ordinary day-car, and I do not therefore claim, broadly, a partition between the seats of a railroad-car.

Having thus described my invention, what I claim as new, and desire to secure by Letters
15 Patent, is—

1. A flexible and extensible partition adapt-

ed to be connected to the car in line with the back of the seat, and to be held extended upon said back, whereby the occupants may be secluded or protected, substantially as described. 20

2. A curtain, A, in combination with the roller B, attached to the car, the rod C, and means, substantially as described, for connecting the rod C to the back of the car-seat, as set forth. 25

In testimony whereof I have signed my name to this specification in the presence of two subscribing witnesses.

EDWIN P. OSGOOD.
